CLAIM

The ornamental design for a support tower for a vehicle rack, as shown and described.

DESCRIPTION

FIG. 1 is a front perspective view of a support tower for a vehicle rack;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The broken lines shown in the drawings illustrate portions of the support tower for a vehicle rack in which the design is embodied and forms no part of the claimed design.
